UNITED STATES PATENT OFFICE

ORLANDO W. HART, OF FALL RIVER, MASSACHUSETTS.

SELECTIVE SIGNALING SYSTEM.

No. 901,441.

Specification of Letters Patent.

Patented Oct. 20, 1908.

Application filed August 10, 1907. Serial No. 388,024.

To all whom it may concern:

Be it known that I, ORLANDO W. HART, a citizen of the United States, residing at Fall River, in the county of Bristol and State of Massachusetts, have invented a certain new and useful Selective Signaling System, of which the following is a specification, reference being had therein to the accompanying drawing.

10 My invention relates to signal systems that may be employed, as in connection with railroads.

The principal objects of my invention are, First, to provide means whereby an operator at one place, as a central station, can cause a signal at any one of two or more other places, to be set, and automatically locked in operative position until, in response to it, the person signaling back to the central station, restores it to normal position:

Second, to provide means whereby upon the locking of the signal which has been set, a record of the locking of the signal which has been set, is made at said central station, and indicates that the signal is set, and locked in position;

Third, to provide means whereby a series of selector instruments may be synchronized during the initial part of a signal setting operation; and, if desired, during the final part of the operation also, for additional safety;

Fourth, to provide a selector with a neutral point, so that a tripping circuit controlled by said selector, is disconnected when the selector is in synchronizing position, so that lightning may be prevented from entering the coils;

Fifth, to provide a transmitting device which, by reason of its transmitting wheel, is adapted to be adjusted so as to control certain electrical circuits, that any one of two or more signals, distant from the transmitting device, may, by suitable electro-magnetic devices, be operated;

45 Sixth, to provide unimagnetic armature to effect synchronous selection; the operation of the armature being the same, and independent of the polar direction of the energizing current. In this way the maintenance of a fixed terminal to insure proper direction of current, is eliminated;

Seventh, to provide a selector movement which may be removably secured at any station;

55 Eighth, to prevent snow and ice from interfering with the operation of the signal;

Ninth, to provide means whereby a selector instrument may be quickly adapted for use in connection with any of the signal stations;

60 Tenth, to send a proper current to set a signal, the action of which will break the operating circuit and thus leave the line clear;

Eleventh, to provide an answering circuit of high resistance, and a low operating current to prevent the burning of the break wheel and contact at the stations;

Twelfth, to provide means to operate selector instruments over one circuit, and to set the signal, and to receive the answer back 70 over an independent circuit;

Thirteenth, to provide means for locking the transmitter, to prevent any change being made at any point, except at normal position;

75 Fourteenth, to operate a mechanical switch, or commutator, by means of a motor, which in turn, is released by a break wheel, at each impulse; a quick and positive break being thereby obtained; and any sticking obviated;

Fifteenth, to provide means, beyond the control of the operator, whereby there may be made for only the management, a record of the operation of the bolt, and of the time 85 it was operated;

Sixteenth, to provide means whereby recording paper is supplied to the recording apparatus, only during a fixed period, controlled by the trip and answer back segment 90 of the break wheel of the transmitter;

Seventeenth, to provide means to sustain, release, and restore a signal rod to normal position;

Eighteenth, to provide means whereby a 95 signal system avoids sneak circuits, and is operative under different atmospheric conditions; i. e. is not affected by exposure to weather.

I found in my experiments, which took 100 place in my laboratory in the development of this invention, that the devices and circuits as thus constructed, were such that while they would operate perfectly under cover, they would not operate for any extended period when placed in actual position, out of doors where they were designed to be used. I finally discovered that the real causes of the failure were due to line troubles, grounds, atmospheric changes, which 105 resulted in sneak currents, crosses, and discharges that interfered with the successful

operations of the stations. The circuits and apparatus shown and described herein, overcome among others, all of these objections due to such currents, and may now be used with certainty of action, in the open air. In general, these objections may be said to be overcome by use of a selector circuit and an independent trip circuit, either of which is idle while the other is active.

10 The other objects of my invention and the means employed to accomplish them will become plain hereinafter.

Figure 1 is a diagrammatic view of the wiring, and connections made by the transmitting device; Fig. 2 shows a diagrammatic view of the connections necessary to operate the selector instruments by the transmitter; Fig. 3 is a diagrammatic view showing the necessary wiring controlled by the transmitter for producing reverse currents necessary to release the selector instruments; Fig. 4 is a like view of the electrical connections necessary first, to trip a signal station; second, to bridge a portion of the trip circuit; third, to operate a time stamp printing device; and fourth, to receive and record answer back impulses. Fig. 5 is a like view showing the main wires to which the wiring shown in Figs. 1, 2, 3 and 4 are connected, and to which are connected also the station wires and apparatus employed at the station; Fig. 6 is a side elevation of my transmitter device; Fig. 7 is a plan of same; Fig. 8 is a detail plan of circuit controlling levers, partly in section; Fig. 9 is an elevation of said detail; Fig. 10 is a cross-section on line 10^x—10^x, Fig. 6, particularly to show the method of locking and unlocking the transmitting wheel and tripping and registering segment; Fig. 11 is a detail in cross-section, of said locking means; Fig. 12 is a front elevation; Fig. 13 is a like view, the locking pin and arm moving away from each other; Fig. 14 shows a semaphore provided with its local controlling apparatus; Fig. 15 is a perspective view showing means for supporting, tripping, and restoring the semaphore to normal position; Fig. 16 is a like view, partly in section to show the latch in engagement with its supporting surface; Fig. 17 shows in perspective, the means, illustrated in Fig. 15, but after the semaphore has dropped; Figs. 18, 18^a, 19, 20 and 21 are respectively a front elevation, a side elevation of a detail, a side elevation, an opposite side elevation, and a plan, of selecting and tripping devices located at each signal station; Fig. 22 is a section of Fig. 20, to show one of the trip circuit terminals, and a metal member to be moved into and out of contact with it and its associate terminal; Fig. 23 shows in perspective, the devices shown in Figs. 18 to 22 inclusive; Fig. 24 is a perspective view of my new selector case; Fig. 25 is a front view of station apparatus mounted in a metal case;

the door being open; Fig. 26 is a cross-section on line 26—26, Fig. 25; Fig. 27 is a section on line 27—27, Fig. 25; Fig. 28 is an elevation showing my recording and time stamp apparatus, cooperating with the transmitting device; while Fig. 29 is a plan; and Fig. 30 is an end thereof.

The first general object of my invention is attained by making use of a transmitting device, a signal selecting device, a signaling device, proper electrical circuits for said devices, and a locking device for locking the signaling device in signaling position; while the second is attained by employing the signaling device in combination with a record transmitting device, recording device, and suitable electrical circuits connecting said transmitting device and recording device, all designed to show whether or not the signal required, was set and locked. 85

In the drawings illustrating the principles of my invention, and the best mode now known to me of embodying those principles, are shown, apparatus actually employed upon a single track electric car line with sidings to enable cars to pass when going in opposite directions. It is at these meeting points, called stations, that the signal device of my invention has been demonstrated by experiment, to be of exceeding value, not only as a convenience for calling crews to telephone for orders, but also for guarding against the greatest danger both steam and electric roads have, namely the instability of human memory. It puts a check upon the possible failure of a man's memory, by displaying a signal which, when once set, remains so until one of the crew unlocks it; for no one but one of the crew can unlock it. Further, as the crew knows that a record of every signal set, is automatically made at the central station, and that to go by the signal without unlocking, resetting, and reporting to the central station, would be discovered, the crew unlocks, and resets the signal, and reports for orders. 100 105 110

The first feature of my invention resides in a transmitting device whereby the number and kind of impulses desired, may be automatically sent through the various circuits. 115

The primary selection of the number and kind of impulses, is determined by a transmitting wheel 50, Figs. 6, 7 and 8, mounted upon a shaft 51 in bearings in a frame 52. Movement is imparted to it by any suitable means, and its speed may be controlled, as by a governor 53.

The circumference of the transmitting wheel 50 is spaced, for example, for 66 teeth. For one portion of the circumference, twenty-one or more teeth 54 are cut; there being at least as many of such teeth as there are stations, so that there is a tooth corresponding to its respective station. These teeth may be designated as the primary res. 125 130

toration teeth, and are employed, as will appear in detail later, to insure the restoration of the signal apparatus at each of the stations. The next two spaces 55 for teeth are 5 left blank, so that an impulse reversing circuit lever 58, to be described, resumes normal position, or is at rest, and during said period of rest a pin 57 on the transmitting wheel operates a synchronizing lever 58 for 10 the purpose of completing a reverse circuit, of low current, the purpose of which will be made plain hereinafter. The following forty-one spaces 59 are cut into a corresponding number of teeth; one portion of these teeth, 15 which we will call the selecting portion, being employed to select the signal station wanted, and the other portion, we will call the secondary restoring portion. A trip and registering circuit plate 60 is adjustably secured to the transmitting wheel, and is of such 20 length and form that it renders twenty of said forty-one teeth inoperative; that is, if only one of the selecting teeth is operative, twenty of the restoring teeth are operative; 25 if the position of the plate in relation to the forty-one teeth 59, is changed, and five of the selecting teeth are rendered operative, then sixteen of the restoring teeth are operative; if twenty of the forty-one selecting teeth are 30 made operative, there is only one restoring tooth exposed, and the one selecting tooth becomes the secondary restoring tooth, and after its operation, all the selecting apparatus at the twenty stations is in normal position. 35 The next two teeth spaces are blank, and represent that the transmitting wheel has returned to normal position and completed one revolution. The sixty-six circumferential spaces are now accounted for. This 40 trip and registering circuit plate 60 is free to turn upon the transmitting wheel shaft 51, but it may be secured in its relation to the forty-one teeth 59, upon the transmitting wheel 50, by means of a lock pin 61 mounted 45 in the plate, and adapted to engage each of the twenty holes 62 in the transmitting wheel; each hole being so spaced, that a movement of the plate one hole, renders operative or inoperative the next adjacent tooth of the transmitting wheel 50.

A station dial 63 having thereon figures from 1 to 20, inclusive, and lock holes 63^a, corresponding to the number of signal stations, is fixed to the frame 52. A pointer 64, 55 which has a pin 64^a to engage said lock holes 63^a, and may be moved over said dial, is connected with an arm 65, in operative engagement with the lock pin 61, Figs. 6, 10, 11, fixed in the trip and registering circuit plate 60. The pointer, dial, arm and pin bear such relations to each other, that when the pointer is caused to point, say to No. 5 on the station dial, the arm 65 by its engagement with the pin 61 moves the plate, 60 so that five of the teeth 59 become selecting teeth, and sixteen of the teeth 59, become restoring teeth. If station "15" is in the operator's mind, then when he moves the pointer to No. 15, on the dial, the fifteen exposed teeth constitute the selecting or station 70 teeth, and six, the secondary restoring teeth of the transmitting wheel. In short, by moving the pointer to any particular number on the dial, the corresponding number of selecting teeth and the complementary number of restoring teeth, will be exposed. But to move the lock pin 61 of the trip and registering circuit plate 60 into and out of engagement with the transmitting wheel 50, the arm 65 and the pointer are fixed to the 80 shaft member 66, Fig. 10, having an axis common with that of the transmitting shaft, and being retained in said axis by means of a pin 67 free to be turned in a bearing in the transmitting shaft 51. This construction 85 permits an axial movement of the shaft member 66, pointer 64 and arm 65, to be brought about by the use of a handle 68, secured to the shaft member 66, say, as in the manner shown. A pull upon the handle, 90 away from the apparatus, Figs. 10, 11, 12, disengages the lock pin 61 and the pointer 64 from the transmitting wheel 50, and the dial 63, respectively; and then by turning the handle until the pointer indicates the 95 number of the station wanted, and allowing the handle to be moved towards the apparatus, as by springs 69, 70, respectively, on the arm 65, and the frame 63, and in engagement with the plate 65, and a groove in the 100 shaft member 66^a, (such engagement allowing the springs to operate, notwithstanding movements of the coöperating parts) the pointer 64 becoming fixed to the dial, and the trip and registering circuit plate 60 to 105 the transmitting wheel 50.

In order that the transmitting wheel, plate, and lock pin may be moved together without interfering with the arm 65, (which it is to be remembered, is locked in position 110 by the pin pointer 64^a in engagement with one of the series of holes 63^a in the dial, under the numbers) the lock pin is provided with a head 71 and a neck 72, so that the free end portion of the arm 65, when there is relative 115 movement between the arm and the plate, freely passes by the head and over the neck, as in Figs. 10, 11. When, however, the arm and lock pin are in their stationary and normal positions, Fig. 11, and the arm 65 is 120 next moved away from the plate, then, obviously, a slot 65^a in the free end portion of the arm 65, engages the head 71 of the pin 61, and if a rotary movement is given to the arm by a turn of the handle 68, the arm carries the lock pin, and hence the plate 60 along with it, the transmitting wheel 50 remaining stationary. By allowing the pointer 64, and thus its lock pin 64^a, to move and become locked to the dial, when the pointer 125 130

points to the right number on the dial, the arm 65 allows its lock pin 61 to lock the plate 60 and transmitting wheel 50 together, by moving out of engagement with the head 71 of the lock pin, as in Figs. 10, 11, and into a position such that the head 71 of the pin may pass by the free end of the arm 65, and thus not interfere with a rotary movement of the transmitting wheel 50 and the plate 60, 10 Fig. 13.

The movement desired to be given to the transmitting wheel, may be imparted through any suitable mechanism, as by a weight 80, Fig. 6, acting upon an arm 81 on a shaft 82, 15 and provided with gear teeth that mesh with a pinion 83 operatively connected with the transmitting wheel shaft 51.

The transmitting wheel 50 is designed to revolve once for each complete operation of 20 the transmitter, and, for a reason that will be made plain later, the weighted driving shaft 82 during each cycle of operation, moves, say, only a quarter of a revolution, forward and back; the forward movement being due to 25 the weight 80, and the rearward movement, to the movement of a hand crank 84 fixed to the driving shaft 82. Its forward movement is stopped by the engagement of a lock arm 85, Fig. 7, fixed to the driving shaft 82, with 30 the pin 57, in the face of the transmitting wheel; while the rearward movement is stopped by a pin 87 in the driving shaft 82, which engages the end of a slot 88 in a sleeve 89 on said shaft, the movement of said sleeve 35 being arrested by a lock lever 90 normally resting in a circumferential channel 91, in the hub of the arm 65. I will state at this point that this channel is of such width that when this lock lever 90 does not lie in this groove, 40 i. e. when the transmitter is not in operation, but in its normal position, the pointer 64, and arm 65 are free to be moved axially, enough to unlock the pointer from its dial, and the plate 60 from the transmitting wheel 45 50; but once the transmitter is in operative position and the weight 80 is ready to act, this lock lever 90 lies in the channel 91, and fills up so much of the width of it that the extreme unlocking movement is impossible, 50 until the transmitter has returned to normal position, and the lock lever is out of the channel.

It will now be clear, that by moving the crank handle 84 to its extreme backward 55 limit, the weight 80, acting on the driving shaft, through the gears thereon, the pinion, and the selecting shaft 51, will cause the transmitting wheel 50 to turn, and when the latter has completed one revolution, the lock 60 lever 85, on the driving shaft 82, and the pin 57 in the transmitting wheel will engage each other, and the transmitting shaft will stop in its normal position. But just before this 65 revolution is completed, the pin 87 in the driving shaft, meets the other end of the slot

88, in the hub of the locking lever 90, lifts the latter out of the channel 91, on the transmitting wheel shaft 51, and the pointer 64, and segment 65, after the shaft has come to rest, are free to be set in the manner, several 70 times before, described. But the transmitting wheel and shaft are designed to have all of their movements only in one direction; hence to permit the backward movement of the driving shaft 82 when the weight 80 is 75 lifted, the pinion 83 on transmitting shaft 51 is freely mounted thereon, and has a pawl 92 which engages a single toothed wheel 93 fast to the transmitting shaft 51. By this construction, when the weight 80 is in action, 80 the pawl engages a tooth, and a movement of the transmitting wheel 50 results. When the weight is not acting i. e. when the transmitting apparatus is being moved into position for action, the pawl moves out of engagement with the tooth, and the transmitting wheel remains still.

In order that the speed of the selecting wheel may be uniform, there may be used any suitable speed regulating device, as the centrifugal governor 53, operating through suitable gears and pinions upon the shafts, as shown, all of which is readily understood, without further description.

Having now described the apparatus primarily employed to pick out the circuits and when, I will now explain its operation, and the other devices acted upon mechanically by said primary apparatus.

To insure the restoration of all of the selectors at the twenty stations, to normal position, a selecting or restoring circuit must be completed and broken twenty-one or more times. To do this, the transmitting wheel is set into motion. A selecting lever 100, Fig. 100 7, fast to a shaft 101, mounted in the frame 52, is given a vibratory movement, in one direction by a spring 102 engaging its free end portion, and an opposite movement by the inclined face of each tooth, as 54. This vibratory movement is transmitted through the shaft to a releasing arm 103, Figs. 6, 7, having a lock pin 104 thereon, which, in a way to be later described, controls commutators 105, 105^a, employed to complete 110 the restoring circuit, to restore the selector instruments at the several stations to normal position. The power used to move these commutators, may be a weight 106, or other suitable device. A drum 107 having a coil 120 of cord 108, and the weight 106 is operatively mounted on a power shaft 109 in bearings in the frame. A gear 110 upon this power shaft 109 meshes with a pinion 111 upon a speed regulating shaft 112, controlled, as by 125 a fan 113. Fixed to the opposite free end of the regulating shaft 112, is a regulating arm 114 which is normally held still by the engagement of its locking pin 115, with that 104 of the releasing arm 103. Hence upon 130

each forward and back movement of the releasing arm, due to each operative tooth on the transmitting wheel, the releasing arm stops and then releases the registering arm 5 114, and, as a result, the regulating shaft makes one revolution, for the complete operation of each of the exposed teeth on the transmitting wheel.

Fixed to a commutator shaft 116, also having bearings in the frame, is a pinion 117 upon which there is the same number of teeth as that on the regulating shaft 112. As it meshes with the gear 110 on the drum, the commutator shaft and the regulating 15 shaft revolve simultaneously, and in unison. There are two pair of contacts 1, 2 and 3, 4, in the selecting circuit; one for each of the commutators, 105, 105^a. As these commutators are fixed to the shaft, they complete 20 the circuit, used as a selecting or a restoring circuit as the case may be, once for the action of each exposed tooth on the transmitting wheel.

When the weighted cord 108 has become 25 unwound from the drum, it may be rewound, as by the use of a key; a pawl 120 pivoted on the driving wheel 110 engaging, during this operation, the teeth of a ratchet on the drum. After all of the twenty-one primary restoring 30 teeth 54 have acted, a reversing pin 57 engages the head of the pawl or reversing circuit lever 58 fast to a sleeve 132 on the releasing shaft 101, and, by means of a circuit closing arm 133 integral with the sleeve, a 35 momentary contact is made with two pair of terminals 5, 7 and 6, 8, partly dotted, Fig. 7, to complete a releasing or synchronizing circuit to be explained hereinafter. But while this reversing pin 57 and reversing current 40 lever 58 are in engagement, a make and break contact arm 136, fixed to the transmitting wheel shaft 51, engages two terminals 27^a and 27^b, in the synchronizing circuit, so that a reverse current can flow, only for 45 the period of time the reversing pin 57 and circuit lever 58 are in contact to control the synchronizing impulse, otherwise, if there were no terminals 27^a and 27^b there would be 50 not a momentary, but a continuous flow of current through the resistance H, which would result in an unnecessary consumption of current, and a wasteful heating of the resistance.

The tripping and registering circuit plate 55 60 moves into and out of engagement with a trip and registering circuit lever 139, which by means of a circuit closing arm 140, causes a tripping and registering circuit to be closed at contacts 10, 12, Fig. 7, for each revolution 60 of the transmitting wheel. To this arm 140 is fixed an insulating bar 140^a, having a metallic pin 140^b therethrough to complete the circuit between terminals or contacts 10, 12.

In the head 141, Figs. 8, 9, of the trip circuit lever 139, is a pin 142 which plays in a

slot 143 in the head 144 of the selecting lever 100, the pin and slot being so arranged that when the registering circuit lever engages the trip and registering plate 60, the pin 142 abuts the end of the slot 143, and holds the 70 head out of contact with selecting teeth of the transmitting wheel, until the trip and registering circuit lever 139 disengages the plate, then the selecting lever 100 is operated by the secondary, or exposed teeth, to restore the remainder of the stations to normal position. But just as the trip and registering circuit lever and the plate engage each other, a pin or segment 145 in the plate 60 engages a bridging lever head 146, which in 75 turn is connected to an arm 147, provided with an insulating bar 148, and metallic pins 148^a, 148^b, to simultaneously open and close a bridging circuit, having contacts 13, 14, and a time recording circuit, having contacts 85 149, 150. The reverse current arm 133 is provided with a similar bar and metal pins to make and break the reverse circuit.

I have now described the construction and operation of so much of the transmitting device as is used in completing a primary restoring circuit, a releasing circuit, a selecting circuit, a trip circuit, a time recording circuit, and a secondary restoring circuit.

The resulting electrical impulses brought about by the transmitter, pass through suitable circuits, to be described; and are utilized to operate at each station, means, called a selector. The selector automatically picks out a particular trip apparatus that controls 95 the desired signal, such as a semaphore; and the trip apparatus, selected, is then operated through an electrical circuit, conveniently called a trip circuit, and controlled automatically by the transmitter. This selector 100 is mounted in an iron signal box 160, Fig. 14, fixed to a pole 161, having a semaphore 162 of any desired construction. A semaphore rod 163 is operatively connected with the selector, in a way explained later.

When the door of the box is unlocked and thrown open, the selector appears, as in Figs. 25, 26. The selector is mounted on insulating material, as a piece of slate 170, secured to the back of the box. Brackets 171, fixed to a base which is removably fixed to the slate, sustain at the top and bottom two selector electro-magnets 172, 173, which are in the selecting circuit. An armature 174 is pivotally mounted over the poles of the 120 magnets; while a ratchet wheel 175, free to turn with a shaft 176, in standards 177 on the top bracket, is operated by two spring pawls 178, 179, Figs. 19, 26, secured to the armature 174, and on opposite sides of the 125 ratchet wheel 175. They alternately engage the teeth of the ratchet wheel, upon the downward and the upward movements of the armature; the upward movement being brought about by a spring 180^x, when the 130

magnets are de-magnetized. To prevent the ratchet wheel, for any reason, moving more than one tooth whenever the magnets are magnetized, a brake piece 181, also secured to the armature, engages the moving surface of the wheel, and insures the stoppage of the wheel, at the end of the downward movement of the armature. This ratchet wheel is provided with one tooth for each station, and an extra or neutral tooth by which the ratchet wheel is moved into its normal or synchronous position, so that after the entire number of restoring impulses have been sent by the transmitter, the ratchet wheel will be in its normal position.

In order that each selector may be sure not to pass by and beyond normal position, a pin 182, Figs. 18, 23, in the ratchet wheel shaft 176, when the wheel has moved part of the extra tooth space to assumed normal position, engages a detent 183 on a secondary synchronizing and releasing armature 184 of non-polarized magnetizable material, this armature being moved into position to be engaged by said pin, by the selector magnets 172, 173, whenever they are magnetized, as by the selecting or by the restoring circuit, and being held there by residual magnetism until such time as the weak reverse current releases it and permits the ratchet wheel to move the rest of the extra tooth space before the selecting impulses are sent. An adjustable spring 185, which draws the armature and hence the detent, away from the shaft pin 182, is sufficiently strong to hold the armature away from the cores of the magnets, while the weak reverse current is in the magnets, but not strong enough to overcome the attraction resulting from the main current, or its residual magnetic attraction. The selector ratchet wheels at all of the stations, after the restoring impulses are sent out, are thus locked in normal or synchronous position, preparatory to being released, and then moved by the selecting impulses sent by the transmitter. By completing the reverse releasing circuit, and permitting the weak reverse current to pass through the selector magnets 172, 173, the polarity of the magnets becomes opposite, and the consequent repulsion allows the spring 185 to act and draw the armature 184 out of influence of the magnets. The detent 183 and armature move out of engagement with the lock pin 182, and permit the selector spring 180^x to move the armature 184 to its full extent. The selecting magnets at all of the stations are now ready to respond to the selecting impulses.

Mounted upon the selector wheel shaft 176, is a piece of insulating material 177^a, having fixed thereto a metallic piece 178^x which may be moved into contact with two contacts 179^x, 180, to complete the trip circuit employed to operate a signal. This metallic

piece 178^x is so located in its relation to the lock pin 182 of the selector wheel 175 that whenever a predetermined number of impulses corresponding to the number of the station are sent out by the transmitter, this metallic piece 178^x will be in contact with the trip circuit terminals, 179^x, 180, Figs. 18, 22, 23. Thus upon one selecting impulse, that portion of the trip circuit at station No. 1, will be closed; and ready to be finally completed by the transmitting device. Should the transmitter be set to send two selecting impulses, then by two selecting impulses the selecting ratchet wheel at station No. 2, will cause that portion of the trip circuit at said station to become completed, and ready for transmitter to complete finally the trip circuit. The same rule of operation applies to each succeeding station.

That the selector apparatus may be portable and interchangeable, that is, capable of use at any one of the different stations, it is made detachable from the station box; and the trip circuit completing member 178^x is adjustably secured to the selecting shaft. Fixed to this shaft is a toothed wheel 190, having the same number of teeth as does the ratchet wheel 175, that is, one for each station and one extra or neutral tooth. The insulating member 177^a and the trip circuit completing member 178 thereon, are freely mounted upon the shaft, and a pawl 191 pivoted to the insulating member, may, against the tension of a spring, be raised out of engagement with the toothed wheel. Should it be desirable to use this apparatus, for example, at station No. 4, then by having the pawl engage tooth No. 4, Fig. 23, the trip circuit completing member 178 will, after four selecting impulses, engage the two contacts 179, 180, of the trip circuit. To detachably secure this apparatus to the box of a station, the frame has some latch members; in this case, some of its selecting circuit terminals 200, 200^a, 200^b, 200^c, Figs. 24, 25, 310 adapted to removably engage slotted spring terminal 201 fast to the box; and, instead of employing screws 202 in addition, as in Figs. 25, 26, use can be made of pins 203, Fig. 18^x fixed in the insulation, and designed to engage guide members 204, Figs. 18, 19, 21, forming part of the magnet frame. In order, however, that the selector apparatus may be used at any one of the stations on the line, when used in a multiple circuit, the line drop, that is the drop in potential in the circuit from the generator to the end of the line, must be considered. In multiple circuits, the relative resistance of each station must be equal, in order that each station may take its equal portion of the current on the line. To accomplish this, it is necessary to introduce a high resistance near the source of the electrical supply, and a lower resistance at the end of the line. In this instance, the 130

line drop being great and the potential high, the resistances R' , R'' , R''' , R'''' , are put in series with the selecting magnets at the stations, and are of such resistances as to compensate the line drop. Without these resistances, the magnets of the two selectors would have to be of different resistances, and would operate only in their respective positions on the line. In the case of varying the resistances as R' , R'' , R''' , R'''' , at the stations, and making the selector coils of a standard resistance, the switches will work at any point on the line, and may be interchangeable at will.

15 The movable parts of selector apparatus may be protected, as while the apparatus is carried as in one's pocket, from place to place, by providing a suitable metal casing. A very useful form is shown in Fig. 24. The top bracket 210, two sides 211 and back 212 are cast of suitable metal, while a cover, consisting of top 213 and front 214 is in one piece. To secure the cover to the case, two pins 215 in the front of the bracket 210 engage surrounding holes in the inside of the front of the cover; and a slot 216 in the rear of the top of the cover, engages the shank of a screw 217 in the top of the back of the case. The inner portion of the slot is rimmed out to a size corresponding to that of the screw head, so that when the head is screwed down into the recessed slot, it prevents the withdrawal of the cover.

15 The mechanism controlling the signaling device is also mounted within the iron box 160, Figs. 14, 25, 26, 27. Electro magnets 230, Figs. 25, 26, in the trip circuit are fixed to the back of the box, by a bracket 231, and has an armature 232, by which the signaling device, as the semaphore 162, Fig. 14, may be caused to be released, and displayed. The semaphore rod 163 is operatively connected to a guide rod 233 by an arm 234; this guide rod having suitable bearings within the station box, whereby the rod 233, within certain limits, has free vertical movements. Pivoted in a frame 235, Figs. 15, 16, 25, 27, within the box, is a catch shaft 236, which through the guide rod 233 sustains the semaphore while it is in normal position. The guide rod is slotted, and has pivoted therein a latch 237, the lower end of which rests upon a plane surface 238 cut in the catch shaft 236. This surface is so arranged in its relation to the contacting end 239 of the latch, that a line drawn through the center of the pivot 240 and the contact end 239, will pass through the center of the catch shaft 236 and will be at right angles to the plane contact surface 238 of the shaft. A spring 241 on the guide rod tends to hold the latch in normal position. Fast to this catch shaft are two arms; one a lock arm 242 in operative engagement with the trip armature 232, and the other a restoring and re-

leasing arm 243, with a spring 244, tending to cause the catch shaft, and hence its supporting surface, to move so that the latch will slip off the surface, and permit the guide rod 233, and hence the semaphore rod 163 to drop. Near the free end portion of the armature releasing arm 232^a is a triangular pin 245, which is designed to engage a similar pin 246, on the free end portion of the lock arm 242. The surface of these pins are so designed that when the trip armature 232 is attracted by its magnet 230, its pin 245, Figs. 15, 16, moves out of engagement with the release pin 246 on the lock arm 242, the spring 244 so moves the releasing arm 243 that the latch 237 slips off the catch surface 238, Fig. 16, and the semaphore guide rod 233 drops, and hence the arm 234 and the semaphore rod 163, and the signal is displayed. When the guide rod 233, Fig. 17, falls and with it the semaphore, a pin 240 on the guide rod engages a curved surface or cam 248 on the restoring arm, forces the latter back, and with it the lock arm 242, which, by means of its pin 246, engaging the pin 245 on the trip armature arm 232^a, is held in normal position. Should these pins fail to engage, and the lock arm assume the position shown in dotted lines Fig. 17, then when the guide rod 233, and with it the semaphore, is raised, as 95 by hand, to normal position, the pin 240 on the guide rod, engages a curved shoulder or cam 249 on the restoring arm 243, forces back the latter which is there held by the lock arm 242 with its pin 246, which is at once moved 100 into locking engagement with the pin 245, on the trip armature arm 232^a. The catch surface 238 is now in locking position so that when the guide rod 233 is raised its full length, the latch 237, by reason of spring 105 241, snaps back, engages the catch surface 238, and the guide rod and semaphore are supported in normal position.

It will be noticed that when the guide rod 233 is in normal position, a spring 250, fixed 110 to the box and insulated therefrom, contacts with a pin 251, Figs. 15, 17, 25, on the guide rod 233 at normal position. The pin and the spring constitute part of the trip circuit to ground, hence when the guide rod 233 drops, as in Fig. 17, the trip circuit through the trip magnet is broken. As will appear later, the current, when the trip circuit is broken, can now flow through what may be called the answer back or registering circuit. 120

When the semaphore is set, that is, displayed as, say, a danger signal, a locking device is brought into operation so that no one except the person who has access to the box 160, can exercise any control over the signal. 125 A bell crank lever 260, Fig. 25, pivoted to the frame, is always under tension of a spring 161, pulling on the spring arm 262; and the bolt or lock arm 263 by means of a link 264, connected to a bolt 265, is constantly tending 130

to pull the bolt 265 into locking engagement with the semaphore guide rod 233, Fig. 15, in the box. The length of the guide rod is such that when the rod, and hence the semaphore, 5 has dropped, the bolt moves across the end of the guide rod 233, Fig. 17, and at once enters into locking engagement with it, so that the rod cannot be raised and the signal restored to normal position. While the spring 161, 10 Fig. 25, is required to move the bolt 265, into locking position, yet the bell crank lever 260, link 264, bolt 265, and connected parts are so proportioned and arranged, that, if for any reason, say, the spring 161 should break, or 15 cease to tend to act, the bolt 265 would remain in the position it was in when the spring ceased its action; hence, should the spring so cease while the bolt was locking the semaphore rod, the bolt would continue in locking 20 position to lock the rod until it was restored to normal position; in a manner to be described.

Operatively connected to the end portion of the spring arm 262, is an unlocking rod 266 which depends therefrom, passing through the bottom of the box, and into a second or telephone box 267, Figs. 14, 25, located below the station box; it being understood that only those who have a right to 30 reset the signal, have access to this unlocking rod. Now by pulling down on a hook 268, on this rod 266, with one hand, and by lifting the guide rod and semaphore rod with the other, the bolt 265 uncovers the end of the 35 guide rod, and the latter can be restored to normal position; the bolt, when the unlocking rod is released, abutting against the guide rod, and ever ready to lock the semaphore rod again, the moment it is set.

40 It is advantageous to have a record made at the central or transmitting station, that the desired signal was set and locked.

In order that the station operated may send back to the central station a characteristic message or signal, a registering circuit and apparatus are supplied, whereby a pre-determined code of electrical impulses may be created and sent. Connected to the locking bolt 265 above described, is an arm 280 45 controlling a ratchet wheel 281, of a train of gears. Each time the locking bolt is operated, the ratchet wheel, through suitable gearing, causes a break wheel 282, having a certain arrangement of teeth, characteristic 50 to the operated station, to rotate; and a spring terminal 283 upon the rotation of said wheel, successively engages these teeth, and the break wheel and the spring, being in the now opened trip circuit, which becomes the 55 registering circuit, consequently cause a corresponding number of impulses to pass over the registering circuit, and operate certain registering apparatus, to make the record at the central station.

60 The registering apparatus consists of a cal-

endar time stamp to show at what day, hour and minute, the signal is set; and a recording device to record the answer back signal of the station operated. The apparatus is located at the rear of the transmitting apparatus, 70 Figs. 6, 7, 10. Mounted upon a continuation of shaft 289, Figs. 6, 7, 28, 29, 30, controlled by the transmitting wheel shaft 51, is a gear wheel 290, from which power is derived to move the inking rolls 291, 292, and the paper 75 293 upon which the records are to be made. The paper is drawn off from a reel 299, mounted in standards, and its movements are confined by suitable guide rolls as 295, 296. Two gears 297, 298, of the same size, mesh 80 with the power gear 290, each opposite to the other, moving at the same speed, and in the same direction. Controlled by the trip registering lever arm 140, Fig. 7, which completes the trip and the registering circuit, is a 85 toothed sector 299, and meshing with it is a pinion 300 on a pinion shaft 301, mounted in suitable bearings. This shaft, Fig. 28, has a pinion 302, which meshes with a rack 303, on a rod 304, capable of vertical movements. 90 This rod has guide rolls 295 for the paper, and a third roll 305, which lies below, but not in contact with the paper. Directly above the latter roll is a pointed toothed wheel 306 connected with gear wheel 297 that meshes with 95 the power wheel 290. If now the transmitting wheel 50, Fig. 7, is set in motion, and the registering circuit is closed at the transmitter by the trip or registering lever arm 140 and trip and registering plate 60, Figs. 6 and 7, 100 then the meshing sector 299, pinion 300, shaft 301, pinion 302, and rack 303, Fig. 28, cause a vertical movement of the rod 304 and the paper roll 305; the paper 293 is pushed into contact with the pointed toothed drawing in 105 paper wheel 306, and the paper begins to move, and continues so to do until the registering lever arm 140 returns to normal position, at which time the rod 304, with guide rolls 295, is pulled down and the paper no 110 longer engaging the drawing wheel, stops. During this registering period, and only during this period, that is, while the registering segment and the trip and registering lever engage each other, does the paper move. The 115 registering circuit being completed at the transmitting device during this time, the answer back apparatus at the called station, operates; completes the registering circuit; a 120 registering magnet 307 is energized; its armature 308, located beneath the paper, has moved the paper up into contact with the inking roll 292, the number of times, and in the manner, characteristic of the station operated.

125 At the time when the bridging lever arm 147 of the transmitter completes the trip circuit, it also bridges and completes a time recording circuit; and the resulting impulse energizes a time recording magnet 309, which 130

in turn causes its armature 310 to force the recording paper, up into contact with any suitable time recording device 310. This construction and operation of the transmitter, the selecting apparatus, the signaling apparatus, and the registering apparatus, having been explained, their combined action will now be described, reference being had to their electrical connections, which are dia-
10 grammatically shown in Figs. 1, 2, 3, 4, 5.

The electrical current employed is that which, for example, is derived from a proper generator T. The transmitter is electrically connected with the signal station by three wires 1, 2, 3; two, 1, 2, employed by the selecting impulses, and by the synchronizing impulses; while the third wire, 3, is used for the trip impulse, and for the registering impulses. The wiring used for the time recording impulse is at the transmitter station only. For the sake of illustration, a signal is to be displayed at station No. 13. The station pointer handle 68, Figs. 6, 7, of the transmitter is pulled out, and turned so that the station pointer 64 is over the number 13, on the dial 63. When in that position, the handle is released, springs 69, 70, cause the arm 65 to push the pin 61 into the proper hole 62 in the transmitting wheel 50; the pointer 64 be-
20 comes fixed to the dial by the pointer pin 64^a; and the registering plate 60 which was disengaged from the transmitting wheel 50, becomes locked to said wheel. Of the forty-
25 one selecting teeth 59, the registering plate 30 60 has exposed thirteen for controlling the selecting impulses; twenty are rendered in-
operative during the period required for the action of the tripping and registering apparatus; and eight are left uncovered for send-
35 ing the eight impulses remaining of the twenty-one selecting impulses, for returning the selector wheels at the eight remaining stations to normal position. The trans-
40 mitter is now ready for the power to be applied
45 to set in automatic operation, the entire system. The power handle 84, Fig. 6, is moved to its full limit to the left, and then released. The weight 80 starts the transmitting appa-
50 ratus into motion. Each of the twenty-one or more primary restoring or synchronizing teeth 54 of the transmitting wheel engages the selecting lever 100, and its resulting for-
55 ward and back movements control through the releasing arm 103, the number of revolu-
tions of the commutators 105, 105^a, and the limit of the same to the number of primary restoring teeth. Each time the commutators engage the brushes 1, 2, and 3, 4, an im-
pulse passes from the generator T, Figs. 1
60 and 2, through wire 21, main fuse B, wire 22, the brushes 4, 3, and commutator 105^a, wires 23, 24, line wire 1, through each of the twenty stations, i. e. through wire 40, fuse B, Fig. 5, compensating resistances, as R',
65 wire 40, through each selector magnet 172,

173, Figs. 19, 23, 25, wire 41, fuse, line wire 2, brushes 2, 1, Figs. 1 and 2, and commutator 105 at the transmitter, wire 27, to ground G. During these primary restoring impulses, each synchronizing armature 184, Figs. 25, 70 23, at each station is magnetized and its detent 183 moves into the path of the synchronizing pin 182 on the selecting shaft 176. All of the stations now are, or ought to be, in their normal positions.
75

The next operation of the transmitter is to unlock each of the twenty selecting or ratchet wheels 175. To do this, a weak current is caused to flow through each of the selector magnets 172, 173, but in a direction opposite 80 to that required for the operation of selecting. The make and break arm 136, Fig. 7, on the transmitting wheel shaft 51, moves into contact with the contacts 27^a, 27^b, in the reversing circuit, and the reversing pin or 85 segment 57 on the selecting wheel 50, Figs. 6, 7, of the transmitter, engages the reverse current lever 58, and moves it so that it completes the releasing circuit at terminals 5, 7, and 6, 8, Figs. 1, 3, 7, and the current flows from the generator T, Figs. 3, 7, through wire 21, fuse, wire 28, resistance coils H, wire 30, contacts 8, 6, circuit closing arm 133, wire 25, wire 2, selector magnets 172, 173, at each station, wire 1, wire 24, contacts 7, 5, 90 arm 136, contacts 27^a, 27^b, wire 27, to ground G. The polarity of the selector magnets being thus changed, the opposite polarity of the synchronizing armature 184 which together with the force of the spring 185, causes the 100 armature and the detent 183 thereon to move out of the path of the pin 182, on the selecting shaft 176, and all of the selecting wheels at the stations move rearwardly, each of the remainder of its tooth space, and said wheels 105 are ready to respond to the action resulting from the energization of the selector magnets. Next, thirteen selecting impulses are, through the operation of the thirteen exposed selecting teeth 59 on the transmitting wheel, sent 110 through the selecting circuit in the manner already described and shown in Fig. 2, for the primary restoring circuit. Each selector magnet 172, 173, Fig. 23, responds and causes its selecting wheel 175 to move 115 through the space of thirteen teeth. It will be noticed, however, that none of the twenty stations, except No. 13, will have its trip circuit contacts 179^x, 180, in contact with the metallic piece 178 controlled by the selecting 120 wheel shaft 176. All of the selector wheels at the stations having come to a state of rest, and the trip circuit at station 13 having been alone selected of the twenty, for operation, the transmitter is now ready to send through 125 the trip circuit, a tripping impulse to set the signal.
130

After the selecting impulses have been sent, the trip and registering segment 60 controls three of the levers 100, 139 and 146. 130

The pin 142 in the arm 139 engages the slot 143 in the head 144 of the selecting lever 100 and holds it inoperative during the period while the trip and registering lever 140 is 5 performing its function, as shown in Figs. 8, 9. At the time of contact of the trip lever 139 with the trip segment 60, the bridging lever 147 by means of the pin or segment 145 on said segment, is actuated for the period of 10 one tooth of the transmitting wheel 50, and closes two circuits, one of which controls the printing mechanism of the time stamp 310, Fig. 28, and the other bridges across a portion of the resistance I, Figs. 1, 4, and the 15 registering magnet 307. By so doing a current is sent on the line to set the signal, much heavier than is used to record the answer back. It is not necessary to resort to this means, but it has been found that a heavy 20 current will soon burn the break wheel and contact spring at the station, and thus render them inoperative. When the segment 145, on the trip and registering segment 60 has moved out of engagement with the bridge 25 lever 146, the latter returns to normal position and opens the time stamp circuit, and also removes the bridge across the resistance I and the registering magnet 307, and restores said resistance and magnet to the circuit; and a record of the answer back may be 30 made.

The trip and registering plate 60 of the transmitter, engages the trip lever 139 which completes the trip circuit at the trip contacts 10, 12, Fig. 7, the trip current flowing from the generator T, Figs. 1, 4, through wire 21, fuse, wire 28, resistance coils I, wire 33, bridging contacts 14, 13, trip contacts 10, 12, wire 31, line wire 3, wire 42, fuse, Fig. 40 5, trip contacts 179^x, 180, at station No. 13, metallic piece 178^x, wire 43, trip magnet 230, wire 44, spring 250, Figs. 15, 25, pin 251, semaphore rod 233, wire 45, Fig. 5, and ground G. This impulse energizes the trip 45 magnet 230, Fig. 25, the armature 232 releases the releasing arm 242 on the catch shaft 236; the spring 244 acting on the arm 243, turns the catch shaft 236 partially over; the latch 237 slips off the catch surface; and 50 the guide rod 233 and semaphore drop. The trip circuit is therefore broken by the separations of contact pin 251 and the spring contact piece 250. When the guide rod has reached the limit of its downward movement, 55 the locking bolt 265, operated by the coil spring 261, acting through the bell crank lever 260, and link 264, moves in its guides. The end of the guide rod now being below the bolt, Fig. 17, is prevented from any upward 60 movement, by means of the bolt, and therefore the semaphore remains set or in a danger position, until it is restored by a person authorized to open the telephone box 267, Fig. 14. But by this movement of the locking 65 bolt, and hence of the link 264 and arm 280,

connected to the train of wheels, the break wheel 281 with its characteristic teeth, indicating the station No. 13, revolves, and in so doing, it being in the trip circuit and grounded, there are sent over the registering 70 circuit, impulses the characteristics of which are determined by the contacts between the contact piece and break wheel.

The registering or answer back impulses pass from the generator T, Figs. 1 and 4, 75 through wire 21, fuse, wire 28, the resistance I, wire 35, register magnet 307, wire 34, trip and register contacts 10, 12; wire 31, line 3, wire 42, selector contacts 179, 180, metallic piece 178, wires 43, 47; spring terminal 283, Fig. 25, break wheel 282, and ground G. The trip registering lever 139 being held by the registering plate or segment 60, so as to complete the registering contacts 10, 12, at the transmitter, the recording paper 293, Fig. 28, is held up against the pointed teeth of the drawing-in-roll 306 of the registering apparatus, and moves through the guide rolls 295, as already explained, until the registering lever disengages the registering plate. But during this registering period, the characteristic impulses indicating station No. 13, energize the registering magnet 307, Fig. 28, accordingly; the registering armature 308, in turn, presses 95 the paper against the ink roll 292, and the resulting marks indicate that the semaphore at station No. 13, is set and locked. But it will be plainly seen that before any return signal indicating station No. 13 is sent, the 100 signal or semaphore is locked in a danger position. Upon receipt of this return signal, the operator at the central station is absolutely certain that the signal is in a reverse position and properly locked. In this position, it is beyond the control of any unauthorized person. If there is no return signal registered, the operator at once knows that the bolt 265, Fig. 25, has not operated, perhaps because the spring 161 is broken; or if, 105 for example, a long black line appears upon the recording paper, it may mean that, perhaps the bolt has been partially moved, and stopped, leaving the grounded spring terminal 283, in contact with one of the teeth of the 115 make and break wheel 282; the registering magnet 307 remaining energized, and pressing the paper against the ink roll 299, until the registering circuit is broken at the registering contacts 10—12, by the transmitter 120 at the central station; or said long black line may mean that the trip or registering circuit is grounded elsewhere than at the signal station. In fine, by means of the registering apparatus, the operator at the central station 125 knows whether the semaphore rod at the desired signal station, is, or is not locked.

On the segment 60 is the segment or pin 145 occupying a single tooth space of the wheel, and so designed as to operate the 180.

lever 146 drawing its arm 147 at its outer end, the bar 148 of insulating material carrying the contact pins 148^a, 148^b. These pins close for the period of a single space, two circuits, one to control the time stamp, and the other to bridge, as just described, a certain portion of the tripping circuit to obtain more current for the tripping operation.

The time stamp circuit is made up as follows: generator T, Figs. 1, 4, wire 21, fuse block, wire 28, resistance 1, wire 35^a, time stamp magnet 309, wire 35^b, contacts 149, 150, contact pin 148^b, Fig. 7, wire 35, to ground G. The bridging circuit begins at generator T, wire 21, fuse, wire 28, resistance 1, wire 33, contacts 13, 14, and contact pin 148^a, wire 31, line wire 3, Fig. 5, to the original trip circuit already pointed out.

When the trip and registering segment 60 operates lever 139 and the lever 58, the lever 100 must be held in a normal position, so that the commutator will be held at rest. It will be seen that unless means were provided to attain this end, the lever 100 would follow the teeth covered by the segment 60, on the transmitter wheel 50, and would therefore prevent the stations on the line remaining at rest during the time of tripping the semaphore, and receiving and recording the answer back signals, and should the lever 100 operate it would instantly disconnect the station selected, and there would be no answer back. To attain this end the pin 142 is rigidly fastened to the head 141 of lever 139, working in the slot 143 in head 144, of lever 100, so designed that when lever 139 is at rest, the said pin in no way interferes with the operation of the lever 101. But when plate 60 operates lever 139, the pin 40 is forced to the back part of the slot 143, and prevents its action during the time that plate 60 is engaging lever 139. The registering plate having moved out of engagement with the trip lever 139, the selecting lever 100 is freed, and the latter successively engages the remaining eight teeth, and eight more impulses are sent through all of the selecting magnets, as shown and already described in Figs. 1 and 2, so that after these eight impulses have been sent, the selector wheels have the synchronizing pins 182, on their shafts 176, in engagement with detents 183, on synchronizing armature 184; that is, all the stations are ready to be unlocked by the weak reverse current and respond to the next proper impulse.

It has been noticed, that the transmitting wheel is provided with an additional set of teeth. These teeth are provided simply to guard against a failure, for any reason, of some of the selecting apparatus at the station to return to normal position, and by the additional impulses to bring any of the stations that have fallen behind the others, up to their proper synchronizing or starting

points. After the operation of the restoring teeth remaining after the answer back or setting of the signal has been accomplished, reverse current segment or pin 57, Fig. 7, engages a lock arm 85 on the power shaft 82, 70 and the transmitter stops in its normal position. However, just before reaching this position, the pin 87, on the power shaft 82, engages the end of the slot 88 in hub of the station pointer lock arm 90, and raises the lock 75 arm out of the circumferential groove 91 in the station pointer shaft member 66, so that while the transmitter is at a state of rest or in its normal position, the station pointer and connecting apparatus may be moved over 80 the entire face of the station dial; but when the transmitter has once begun to operate, the pointer cannot be changed until after the entire series of operations above described, has come to an end. 85

In a system operated as described, the multiple circuit which operates the selective switches is sometimes used as a telephone circuit, and when so used, has to be transposed, but whether this multiple circuit is straight 90 or transposed, the selectors are still operative.

It will be noted, in connection with the second or trip circuit 3, Fig. 1, that electrically, the selecting circuit 1, 2, is utterly independent of it; that the selecting circuit, as, 95 for station 1, is completed at the central station by the transmitter, as, at the contacts 1, 2, 3, 4; and after the selecting impulses have been sent, the metallic piece 178, at said desired station, is left in contact with the trip circuit terminals 179^x, 180, Figs. 1 and 23; that next, the trip circuit is completed by the transmitter, at contacts 13, 14, but not until the transmitter has caused the selection of the desired station, and has 100 broken the selecting circuit, and the tripping circuit is ready to be completed at and by the transmitter. It will also be seen that if, for any reason, line 3 becomes grounded, all 105 of the selecting magnets at all the stations will respond to the selecting impulses sent by the transmitter, at the central station. In other words, many possible objections due to sneak circuits, and to crosses, are obviated by the use of a selecting circuit and a 110 trip circuit that are electrically independent of each other; and a transmitter device to control said circuits successively, i. e. never simultaneously. Further, as each station is arranged in multiple in relation to the selecting circuit and the trip circuit, then if any 115 one station becomes inoperative, it does not interfere with the proper actions of the others. 120

While my invention is of great utility 125 when used in connection with railways, it is obvious that it can be used successfully in other environments and for other purposes, as for example, in connection with a fire alarm system, a police system, or where it is 130

desirable to call attention of parties in different locations.

It being understood that those skilled in the art to which this invention appertains, once knowing the principles of my invention, can embody the same in different forms without departing from the spirit of my invention, I desire to protect my invention in the broadest manner legally possible.

10. What I claim is:—

1. A transmitting device; a distant signal, at a station; means controlled by said transmitting device, to set the signal; means whereby the signal becomes locked when the signal is set; means operatively connected with said locking means whereby a sign characteristic of the station may be made when the signal is set and so locked; manual means at the station to restore all of said above 15 mentioned apparatus to normal position.

2. A transmitting device; a distant signal; a rod operatively connected to said signal; means controlled by said transmitting device to cause the signal to become set; a bolt to 20 engage, and means to cause said bolt to engage, said rod when the signal is set; means operatively connected to said bolt, whereby when said bolt engages the rod after the signal is set, electrical impulses characteristic of the 25 station may be sent; means whereby said impulses may be received, and cause signs corresponding to the impulses to be made.

3. A transmitting device; a distant signal; a rod operatively connected to said signal; 30 means controlled by said transmitting device to cause the signal to become set; a locking bolt to engage, and means to cause said bolt to engage, said rod when the signal is set; means operatively connected to said bolt, 35 whereby when said bolt has engaged the said rod after the signal is set, electrical impulses characteristic of the station may be sent; a registering device and connecting means, whereby said impulses may be received, and 40 cause signs corresponding to the impulses to be made.

4. A signal; a rod connected therewith; means to hold the signal in normal position; means to set the signal; means to lock the 45 rod when the signal is set; means whereby a sign characteristic of the station may be made; mechanical means at the station to restore said apparatus to normal position.

5. A signal; a rod connected therewith; 50 means to hold the signal in normal position; means to set the signal; a bolt to lock the rod when the signal is set; means operatively connected to said bolt, whereby a sign characteristic of the station may be made; means 55 to restore said apparatus to normal position.

6. A signal; a rod connected therewith; means to hold the signal in normal position; means to set the signal; means to lock the rod when the signal is set; a train of wheels

operatively connected to said locking means; 65 an impulse wheel operated by said train, and having teeth thereon, characteristic of the station; a spring to be engaged by said teeth; said contact and teeth-forming part of a return signal registering circuit; means to restore said apparatus to normal position.

7. A signal rod; a sustaining member pivoted to said rod; a rotatable supporting member; a seat having a diametrical plane surface in said supporting member; said surface, when said sustaining member is in normal position on said surface, being at right angles to a line drawn through the point of engagement and the pivoted point of the rod; an electro-mechanical means for holding and 70 releasing the same.

8. A signal rod; a sustaining member pivoted to said rod; a rotatable supporting member; a seat in said member having a diametrical plane surface, all being designed 75 so that when the said sustaining member is supported in normal position upon the diametrical plane surface of said rotatable supporting member, the points of contact between the said sustaining member and the 80 said surface lie in the longitudinal axis of the said rotatable supporting member; and the weight of said rod acting through the said pivoted sustaining member upon the rotatable supporting member, has no tendency to 85 turn said rotatable sustaining member about its longitudinal axis; and electro mechanical means for locking and releasing the said rod.

9. A signal rod; a sustaining member pivoted to said rod; a movable supporting 100 member having a diametrical plane surface; said surface, when said sustaining member is in normal position, being at right angles to a line drawn through the point of engagement and the pivoted point of the rod; electromechanical means for holding and releasing the sustaining member so that the said 105 line may no longer form a right angle with said surface, and the sustaining member slides off of the supporting surface, and the 110 rod and signal move into a set position; a trip circuit having a trip magnet therein; a trip magnet armature; and a lock arm attached to said supporting member, and adapted to be moved into, and out of, locking engagement with the trip armature; and means to aid said supporting member to turn, when the trip armature, by being operated by the magnet, disengages the lock 115 arm; the sustaining member disengaging the supporting surface and permitting the rod to fall, and thus to set the signal; and means controlled by said rod to open and to close the trip circuit.

10. A signal rod; a sustaining member 120 pivoted to said rod; a movable supporting member having a diametrical plane surface; said surface, when said sustaining member

- is in normal position, being at right angles to a line through the point of engagement and the pivoted point of the rod; means for moving the supporting member so that the said line no longer forms a right angle with said surface, and the sustaining member slides off of the supporting surface, and the rod and signal move into set position; a trip circuit having a trip magnet therein; a trip magnet armature; a lock arm attached to said supporting member, and adapted to be moved into, and out of, locking engagement with the trip armature; means to aid said supporting member to turn, when the trip armature, by being operated by the magnet, disengages the lock arm; the sustaining member disengaging the supporting surface and permitting the rod to fall, and thus to set the signal; and a contact in engagement with said rod when said rod is in normal position; said contact and rod then being electrically connected and forming part of the trip circuit, which is broken at said spring, when the rod descends.
11. A signal supporting rod; a sustaining member pivoted to said rod; a movable supporting member having a diametrical plane surface; said surface, when said supporting member is in normal position, engages said sustaining member, being at right angles to a line drawn through the point of engagement and the pivoted point of the rod; means for moving the supporting member so that the said line no longer forms a right angle with said surface, and the supporting member slides off of the sustaining surface, and the rod and signal move into set position; a trip circuit having a trip magnet therein; a trip magnet armature; a trip armature lock arm, and a restoring arm attached to said supporting member; means to cause said supporting member to turn, when the trip armature, by being attracted by the magnet, disengages the lock arm; the sustaining member disengaging the supporting surface and permitting the rod to fall, and thus to set the signal; an electrical contact in engagement with said rod when said rod is in normal position; said contact and rod then being electrically connected and forming part of the trip circuit, which is broken at said contact when the rod descends; and means whereby said restoring arm may slidingly engage said rod, so that an upward movement and a downward movement of the rod causes the arm to move the trip lock arm into locking position with the trip armature, and the sustaining member into position to be engaged by the supporting member, after said trip circuit is broken, and thus support the rod and its connected signal, when returned to normal position; and a spring to engage said restoring arm while said arm is in normal position, to move the trip armature lock arm out of engagement with the trip armature, to cause the sustaining member to slip off of the supporting surface.
12. A signal device at a station, operated from a distant point; a locking bolt to engage and to lock said signal device after its operation; means whereby the bolt is held normally under tension by engagement with said signal device; said means and bolt being so designed that the bolt will remain in locking engagement with said signal device, independently of said tension, should said tension cease; and manual means at said station to restore the said signal device, bolt and tension means to normal position.
13. A signal device at a station, operated from a distant point; a locking bolt to engage and to lock said signal device after its operation; means whereby the bolt is held normally under tension by engagement with said signal device; said means and bolt being so designed that the bolt will remain in locking engagement with said signal device, independently of said tension, should said tension cease; means attached to said bolt to transmit to said distant point, a characteristic signal, the presence of which denotes a perfect action of the bolt, and the absence of which shows a faulty action of said bolt; and manual means at said station to restore the said signal device, bolt and tension means to normal position.
14. A locking bolt; an electrically controlled distant signal device, holding said bolt in an unlocked position; means for transmitting intelligence of the action of said bolt or lock when the signal is in the desired position to be locked; means to receive, register and time the action of said bolt at a distance; manual mechanical means at the locking bolt to unlock said bolt and restore all the apparatus to normal position.
15. A signaling device at a station; a locking bolt normally held under tension by said signal device, and so designed as to remain in locking engagement with the signal device, until means are used at said station to restore said signal to normal position.
16. A signal rod vertically mounted; an auxiliary supporting rod vertically mounted parallel thereto, and extending downward through the bottom of the case parallel to signal rod; means to connect rigidly the rod and said auxiliary rod; a suitable case; apparatus mounted in the case to control the movements of the auxiliary rod; all designed to do away with an opening in the roof of the case, for the rod, and thus to exclude water and moisture resulting from the elements.
17. A selecting device comprising an electro-magnet in a selecting circuit; a selecting ratchet wheel mounted upon a shaft in suitable bearings; and having teeth thereon; an

armature controlled by said magnet and provided with means to engage said ratchet wheel successively to move said selecting wheel; two terminals in a trip circuit; an insulated metallic member controlled by said selecting wheel to be moved into and out of contact with said terminals, after a predetermined number of movements of the selecting wheel; releasing means fixed to said shaft; a 10 unimagnetic armature, adjacent to said magnet, and designed to be moved into and out of position, to be engaged by said releasing means; and means, adapted to act upon the said armature, in opposition to the normal attractions of the magnet, due to currents which energized the same:

18. A selecting device comprising an electro-magnet in a selective circuit; a selecting ratchet wheel mounted upon a shaft in suitable bearings, and having teeth thereon; an armature controlled by said magnet and provided with means to engage said teeth successively to move said selecting wheel a predetermined number of times; a releasing pin fixed 25 in said shaft; a unimagnetic armature with a detent thereon, adjacent to said magnet, and designed to be moved into and out of position to be engaged by said releasing pin, and a spring, adapted to act upon the said armature, in opposition to the normal attractions of the magnet, due to the current energizing it; two terminals in a trip circuit; an insulated member movably mounted upon said shaft, and having a metallic member fixed therein 30 to engage the terminals in the trip circuit; a wheel with locking teeth, fixed to said shaft; locking pawl mounted upon said movably mounted member, to engage said teeth, so that the metallic member may be caused to 35 contact the trip terminals after a predetermined number of selecting impulses have energized the selecting magnet; all designed so that the selecting device may be set to complete the trip circuit after any desired number of selecting impulses.

19. In a selecting device, a ratchet wheel mounted on a suitable shaft in bearings and having one tooth for each station, and an extra or neutral tooth; an electro-magnet 40 signed to the controlled by a selecting circuit; an armature therefor; a pawl on said armature, to engage each tooth, and move it a portion of its space; a pawl, also on the armature, to engage a tooth on the opposite 45 side of the wheel, and to move said wheel the remaining portion of said tooth space; an escapement on said armature to hold said wheel after it has completed each of its partial tooth movements; a stop pin in said shaft; a 50 unimagnetic armature having means to engage said stop pin, when the neutral tooth has been moved a portion of its space, and permit the rear part, when said armature disengages said pin, to cause the wheel to move 55 its remaining portion of its tooth space, in

response to the first selecting impulse, and leave the selector in its starting position.

20. In a selecting device, a ratchet wheel mounted on a shaft in bearings and having one tooth for each station, and an extra or 70 neutral tooth; an electro-magnet designed to be controlled by a selecting circuit; an armature therefor; a pawl on said armature, to engage each tooth, and move it a portion of its space; a pawl, also on the armature, to engage a tooth on the opposite side of the wheel, and to move said wheel the remaining portion of said tooth space; an escapement on 75 said armature to hold said wheel after it has completed each of its partial tooth movements; a stop pin in said shaft; a unimagnetic armature having means to engage said stop pin, when the neutral tooth has been moved a portion of its space, and permit the rear part, when said armature disengages 80 said pin, to cause the wheel to move its remaining portion of its tooth space, in response to the last selecting impulse, and leave the selector in its starting position; a metallic member, movably mounted on the 85 shaft, insulated therefrom, designed to complete a trip circuit; a lock wheel having teeth corresponding in number to those on the selecting wheel; a pawl operatively connected to the support of the metallic member, and so 90 arranged that while the pawl is in engagement with any one of the lock teeth, the metallic member can engage the trip terminals, 95 at the proper point.

21. A removable selector instrument having insulated terminals thereon to engage fixed insulated terminals of a station; means for guiding and holding said selector in position independent of said terminals to sustain said instrument; a metal protecting case having a removable cover and so designed as to protect the selector during transportation.

22. In a removable selector case, a back; a shelf fastened thereto; an L-shaped cover with proper means to lock the same in a protective position; insulated contact terminals on said back to engage slotted contacts on a signal box; and guides to enable said selector case to be quickly removed from and mounted in said signal box.

23. A transmitting device; a selecting circuit; a selecting device; a trip circuit; means controlled by the selecting device to close the trip circuit; a signal; means controlled by the trip circuit to release and set the signal; 120 means for the signal to open said trip circuit; means to lock the signal in set position; means to register that the signal has been set and locked; and means to restore the signal and co-operating mechanism to normal position; said transmitting device being distant from the said co-operating mechanism, at the signal.

24. A transmitting device, comprising a transmitting wheel; a movable segment 130

thereon; means to adjust and secure said segment to said wheel; a multiplicity of electrical contact making and breaking devices operated by said transmitting wheel and segment; all designed so that the transmitting wheel and the segment may, by adjustment, be capable of operating the making and breaking devices in the order, and at the periods desired.

10 25. A transmitting device comprising a motor moved break wheel; a movable segment on said wheel; means for adjusting said segment to said wheel; a multiplicity of contact making and breaking devices operated by said wheel, and said segment; said wheel, segment and contact making and breaking devices being so arranged, as first, to control a synchronizing circuit to bring all station selecting selectors, in the signal circuit to a common starting point; second, to control a release circuit to start selecting apparatus at all of the stations, in step; third, to control a selecting circuit; fourth, to control a trip circuit, as to bridge resistance and a register magnet in said circuit, and to set the signal; fifth, to restore said resistance and magnet to the circuit which becomes a recording circuit; and sixth, to control a selector restoring circuit.

30 26. A transmitting device comprising a motor moved break wheel; a movable segment on said wheel; means for adjusting said segment to said wheel; a motor operated commutator released by said break wheel, and a multiplicity of contact making and breaking devices operated by said wheel, and said segment; said wheel, segment and contact making and breaking devices being so arranged, as first, to control a synchronizing circuit to bring all station selecting instruments in the signal circuit to a common starting point; second, to control a release circuit to start selecting apparatus at all of the stations, in step; third, to control a selecting circuit; fourth, to control a trip circuit, as to bridge resistance and a register magnet in said circuit, and to set the signal; fifth, to restore said resistance and magnet to the circuit which becomes a registering circuit; and sixth, to control a restoring circuit.

27. A transmitting device comprising a motor moved break wheel; a movable segment on said wheel; means for adjusting said segment to said wheel; and a multiplicity of contact making and breaking devices operated by said wheel, and said segment; said wheel, segment and contact making and breaking devices being so arranged, as first, to control a synchronizing circuit to bring all station selecting switches, in the signal circuit to a common starting point; second, to control a release circuit to start selecting apparatus at all of the stations, in step; third, to control a selecting circuit; fourth, to control a trip circuit, a time recording circuit,

and to render inoperative a series of resistance coils and a register magnet in said circuit, by means of a bridging contact, and to set the signal; fifth, to restore said resistance and magnet to the circuit which becomes a registering circuit; and also to open the time recording circuit; and sixth, to control a restoring circuit; and means for preventing the changing of the combination of the break wheel and the segments until they have performed their proper functions.

28. A transmitting device comprising a motor moved break wheel; a movable segment on said wheel; means for adjusting said segment to said wheel; and a multiplicity of contact making and breaking devices operated by said wheel, and said segment; said wheel, segment and contact making and breaking devices being so arranged, as first, to control a synchronizing circuit to bring all station selecting switches, in the signal circuit to a common starting point; second, to control a release circuit to start selecting apparatus at all of the stations, in step; third, to control a selecting circuit; fourth, to control a trip circuit; a time recording circuit to be operated at the point of bridging a series of resistance coils and a register magnet in the said trip circuit, and to set the signal; fifth, to restore said resistance coils and magnet to the circuit which thus becomes a registering circuit and with the same operation open the time recording circuit; and sixth, to control a restoring circuit; and means for preventing the changing of the combination of the break wheel and the segments until they have performed their proper functions.

29. A transmitting device comprising a motor moved break wheel; fixed and movable segments on said wheel; means for adjusting said segments to said wheel; a motor operated commutator released by said break wheel, and a multiplicity of contact making and breaking devices operated by said wheel, and said segment; said wheel, segment and contact making and breaking devices being so arranged, as first, to control a synchronizing circuit to bring all station selecting selectors, in the signal circuit to a common starting point; second, to control a release circuit to start selecting apparatus at all of the stations, in step; third, to control a selecting circuit; fourth, to control a trip circuit, as to bridge resistance and a register magnet in said circuit, and to set the signal; fifth, to restore said resistance and magnet to the circuit which becomes a recording circuit; and sixth, to control a restoring circuit; and means for preventing the changing of the combination of the break wheel and the segments until they have performed their proper functions.

30. A transmitting device comprising a motor moved break wheel; fixed and movable segments on said wheel; means for ad-

justing said segment to said wheel; means on the break wheel shaft to make and break a shunt circuit at a predetermined time, to provide a high current to a line, at a voltage lower than that of a selecting circuit; a motor operated commutator released by said break wheel, and a multiplicity of contact making and breaking devices operated by said wheel, and said segment; said wheel, 5 segment and contact making and breaking devices being so arranged, as first, to control a synchronizing circuit to bring all station selecting select 8's, in the signal circuit to a common starting point; second, to control a release circuit to start selecting apparatus at 15 all of the stations, in step; third, to control a selecting circuit; fourth, to control a trip circuit, as to bridge resistance and a register magnet in said circuit, and to set the signal; fifth, to restore said resistance and magnet 20 to the circuit which becomes a registering circuit; and sixth, to control a restoring circuit; and means for preventing the changing of the combination of the break wheel and 25 the segments until they have performed their proper functions.

31. A transmitter having a break wheel; a segment, adjustable thereon; a lever controlled by said wheel; a lever controlled by 30 said segment; means whereby the segment lever when operated by the segment, prevents the break wheel from operating the break wheel lever; and means controlled by said break wheel lever to make and break an 35 electrical circuit.

32. A transmitting wheel mounted in suitable bearings, and provided with a series of selecting teeth; a movable recording segment whereby a fixed number of said teeth may be 40 rendered inoperative; means whereby said segment may be moved to render operative the desired number of teeth, and then be locked to the wheel; a pointer operatively connected to said segment; a dial; the dial, 45 pointer and segment being so arranged that when a number of selecting teeth is rendered operative, the pointer points to that number on the dial; means to cause the transmitting wheel to move; and means, caused to be operated by said transmitting wheel, to make and break electrical circuits.

33. A transmitting wheel mounted in suitable bearings, and provided with a series of selecting teeth; a movable tripping and registering segment, whereby a fixed number of said selecting teeth is rendered inoperative; means whereby said segment may be moved to expose the desired number of selecting teeth, and then be locked to the wheel; a 55 pointer; means whereby the pointer is operatively connected to said segment; a dial; the dial, pointer and segment being so arranged that when a number of selecting teeth are exposed, the pointer points to that number 60 on the dial; and means caused to be operated

by said transmitting wheel, to make and break electrical circuits; a driving shaft, meshing gears to connect the driving wheel and the transmitting wheel shaft; a latch mounted on said driving shaft; a circumferential groove in the said means connecting the pointer and the segment; said latch engaging said groove and preventing any change in the arrangement of the wheel and segment; while the transmitting wheel is out 75 of normal position, but allowing said change when the said wheel is in normal position.

34. A transmitting wheel mounted in suitable bearings, and provided with a series of selecting teeth; a movable tripping and registering segment, whereby a fixed number of said selecting teeth is rendered inoperative; means whereby said segment may be moved to expose the desired number of selecting teeth, and then be locked to the wheel; a 80 pointer; means whereby the pointer is operatively connected to said segment; a dial; the dial, pointer and segment being so arranged that when a number of selecting teeth is exposed, the pointer points to that number 90 on the dial; and means caused to be operated by said transmitting wheel, to make and break electrical circuits; a driving shaft, meshing gears to connect the driving wheel and the transmitting wheel shaft; a latch 95 mounted on said driving shaft; a circumferential groove in the said means connecting the pointer and the segment; said latch engaging said groove and preventing any change in the arrangement of the wheel and segment; while the transmitting wheel is out 100 of normal position, but allowing said change when the said wheel is in normal position; unipolar armature release contacts; means to make and break a circuit through 105 said contacts; and means to make and break a time stamp circuit.

35. A shaft mounted in suitable bearings; a motor operated transmitting wheel fixed thereto; a segment free to turn on said shaft; an axial hole in said shaft; a member provided with a bearing member mounted in said hole; a lock arm secured to said member; means whereby said member may be moved axially in said hole; a series of holes in said wheel; and a pin mounted in said segment to engage any one of said holes; said pin having a head which, when the lock arm is moved away from the segment to set the segment in proper position on the wheel, engages a seat in the lock arm and the pin disengages the wheel; but which, when the pin locks the wheel and segment together, passes freely by said seat.

36. A shaft mounted in suitable bearings; a motor operated transmitting wheel fixed thereto; a segment free to turn on said shaft; an axial hole in said shaft; a member provided with a bearing member mounted in said hole; a lock arm secured to said mem- 125 130

ber; means whereby said member may be moved axially in said hole; a series of holes in said wheel; a pin mounted in said segment to engage any one of said holes; said pin having a head which, when the lock arm is moved away from the segment to set the segment in proper position on the wheel, engages a seat in the lock arm and the pin disengages the wheel; but which, when the pin locks the wheel and segment together passes freely by said seat; a pointer connected to said member; a dial to indicate the number of teeth exposed; circumferential groove in said member; a latch which, while the transmitter is in operation engages said groove; all so designed that the segment and wheel cannot be disengaged by the operator, during the operation of the transmitter.

37. A shaft mounted in suitable bearings; 20 a motor operated transmitting wheel fixed thereto; a segment free to turn on said shaft; an axial hole in said shaft; a member provided with a bearing member mounted in said hole; a lock arm secured to said member; means whereby said member may be moved axially in said hole; a series of holes in said wheel; a pin mounted in said segment to engage any one of said holes; said pin having a head which, when the lock arm is moved away from the segment to set the segment in proper position on the wheel, engages a seat in the lock arm and the pin disengages the wheel; but which, when the pin locks the wheel and segment together, passes freely by said seat; a pointer connected to said member and having a locking pin; a dial to indicate the number of teeth exposed; holes in said dial to be engaged by said pointer pin to lock the pointer in position; 35 circumferential groove in said member; a latch which, while the transmitter is in operation, engages said groove; all so designed that the segment, pin, lock arm and pointer are always in position to be operated while the transmitter is idle, but can not, during the operation of the transmitter, be controlled by the operator.

38. A transmitting device having a transmitting wheel and supporting shaft; a contact making and breaking device operated by said wheel; a sheet of record paper; a feed roll, operatively connected with said transmitting wheel shaft, but just out of contact with said paper; means operatively connected with said contact making and breaking device, whereby when said making and breaking device is operated, said record paper engages the feed roll, and moves only while said making and breaking device is operated; a printing wheel operatively connected with said transmitting wheel shaft, but out of contact with said paper; a registering magnet; and a registering armature; said paper being between said printing wheel and said registering armature; and said

registering magnet being designed to operate at some time while the making and breaking device is in operation.

39. A source of electricity; a selecting circuit; a series of stations; electro-magnets, 70 one at each station, in said selecting circuit; selecting apparatus at each station controlled by energizing said magnets; means to make and break the selecting circuit to energize the electro-magnets; means employed in 75 stopping the selecting apparatus at a common starting point; a releasing circuit; resistances therein; means whereby a weak reversed current may be caused to flow about said selecting magnets at said stations, in a 80 direction opposite to that of the selecting current; apparatus of unimagnetic material provided with means to engage the selecting apparatus to arrest the movement of each of the selecting apparatus at a common starting 85 point; said armature releasing said selecting apparatus, when said weak current of opposite polarity energizes the magnets; means for making and breaking the selecting circuit any predetermined number of times; a 90 drop switch at each station; a trip circuit; resistances and a register magnet therein; a trip magnet in said circuit; means for bridging said register magnet and said resistances while the trip circuit is completed; a trip 95 magnet armature, to control said drop switch or signal in normal position, said drop switch forming a part of the trip circuit; means controlled by the selecting apparatus to complete the trip circuit, energize the trip 100 magnet, and release the drop switch or signal; the trip circuit becoming broken; a registering circuit; a break wheel and a brush to engage the teeth of said wheel, forming part of said registering circuit; and a register 105 magnet in said circuit; means to restore the drop switch to normal position; and means to make and break the selecting circuit a predetermined number of times to restore 110 all of the selecting apparatus at the station to normal position.

40. A source of electricity; a selecting circuit; a series of stations; electro-magnets, 115 one at each station, and in said selecting circuit; selecting apparatus at each station controlled by energizing said magnets; means to make and break the selecting circuit to energize the electro-magnets; means employed in stopping the selecting apparatus at a common starting point; a releasing circuit; resistances therein; means whereby a weak current may be caused to flow about said selecting magnets at said stations, in a direction opposite to that of the selecting current; apparatus of unimagnetic material provided 120 with means to engage the selecting apparatus to arrest the movement of each of the selecting apparatus at a common starting point; said armature releasing said selecting apparatus, when said weak current of opposite 125

130

- 5 polarity energizes the magnets; means for making and breaking the selecting circuit any predetermined number of times; a drop switch at each station; a trip circuit; resistances and a register magnet therein; a trip magnet in said circuit; means for bridging said register magnet and said resistances while the trip circuit is completed; a trip magnet armature, to control said drop switch 10 or signal in normal position, said drop switch forming a part of the trip circuit; means controlled by the selecting apparatus to complete the trip circuit, energize the trip magnet, and release the drop switch or signal; 15 the trip circuit becoming broken; a time recording circuit; electro-magnetic means in said circuit; a time recording device controlled by said means; means whereby the time recording circuit and the trip circuit are 20 simultaneously made and broken; a registering circuit; a break wheel and a brush to engage the teeth of said wheel, forming part of said registering circuit; and a register magnet in said circuit; means to restore the drop switch to normal position; and means to 25 make and break the selecting circuit a predetermined number of times to restore all of the selecting apparatus at the station to normal position.
- 30 41. A selecting circuit; means to use the same; a signal; a trip circuit independent of but operated by said selecting circuit to set the signal; a source of electrical energy; electro-mechanical means in said selecting circuit to open and close the trip circuit; register magnet and resistances in the trip circuit; means to bridge said magnet and resistances; a tripping magnet in the trip circuit; and means for opening the trip circuit 40 when the signal is set.
42. A selecting circuit; means to use the same; a signal; a trip circuit independent of said selecting circuit; a source of electrical energy; electro-mechanical means in said 45 selecting circuit to open and close the trip circuit; a registering circuit; register magnet and resistances in said registering circuit; means to lock the signal, and to send electrical impulses through the registering circuit, characteristic of the bolt operated in the trip circuit; means to bridge said magnet and resistances; a tripping magnet in the trip circuit; and means for opening the trip circuit when the signal is set.
- 50 43. A time recording device; recording paper therefor; a trip circuit; a time recording circuit; electro-magnetic means in the time recording circuit; a transmitting device to close the trip circuit and the time recording circuit simultaneously; all designed so that said electro-magnetic means causes said time recording device to make its record, when the trip circuit is completed.
- 55 44. In a signal system, a balanced multiple circuit having operative unimagnetic selective switches therein; a second circuit having a series of terminals; magnets in said second circuit; a source of electrical energy for said circuit; a transmitting device to close said multiple circuit and energize said switches to close said second circuit and then to send a current through said second circuit to energize one of said magnets; all designed so as to prevent sneak circuits, crosses, and the like from tending to unbalance the said 70 first circuit.
45. In a signal system having signal stations; a selective switch at each station; unimagnetic means for synchronizing each switch; a signal circuit controlling said means, from a distant operating point; means at said operating point to control the action of the said switches; means for generating a source of electrical energy; a second circuit controlled by the said selector 80 switches, but independent thereof, to set a signal; means at the signal station and at the distant operating point to form a circuit to transmit a characteristic signal.
46. In a signal system having signal stations; a selective switch at each station; unimagnetic means for synchronizing each switch; a signal circuit controlling said means, from a distant operating point; means at said operating point to control the action of the said switches; means for generating a source of electrical energy; a second circuit controlled by the said selector 85 switches, but independent thereof, to set a signal; means at the signal station and at the distant operating point to form a circuit to transmit a characteristic signal.
47. In a signal system having signal stations; a selective switch at each station; unimagnetic means for synchronizing each switch; a signal circuit controlling said means, from a distant operating point; means at said operating point to control the action of the said switches; means for generating a source of electrical energy; a second circuit controlled by the said selector 90 switches, but independent thereof, to set a signal; means at the signal station and at the distant operating point to form a circuit to transmit a characteristic signal back to the said operating point, and to register and time the same, at the said distant operating point.
48. A source of electrical energy; a selector signal circuit; signal stations having selector switches controlled thereby; a transmitting device; operating coils for said selector switches and arranged in parallel re- 105

- lation to each selector switch at its respective station and also to the source of electrical energy; a second or signal operating circuit independent of said signal circuit, 5 but controlled thereby; signal operating coils; a drop switch; and means for transmitting a characteristic answer back signal, in the ground connection or side of said second circuit; all so arranged that should 10 the drop switch, the transmitting means, or the operating coils at a station, fail to act normally, information of such failure would be furnished by the non appearance of the characteristic answer back signal; said 15 failure to act normally in no way affecting the action of any of the other stations on the circuit.
49. In a selective signal system, a two wire multiple circuit; interchangeable selector switches operatively connected therein; 20 variable resistances in said circuit in series with said selector switches to balance the relative resistances to the generator and thus compensate a line drop.
50. A transmitting device; a selecting circuit; a selecting device; a trip circuit of low resistance; means controlled by the selecting device to close the trip circuit; a signal; 25 means controlled by the trip circuit to release and set the signal; means at the signal, to open the said trip circuit; means to lock the signal in set position; a registering circuit having a higher resistance than the trip circuit; means to lock the signal in set position; 30 apparatus operated by the means to lock the signal in set position, to send over the registering circuit, impulses characteristic of the signal set; and means controlled by said impulses, to register the fact that the signal has 35 been set and locked.
51. In a selective signal system, a two wire multiple circuit; interchangeable selector switches operatively connected therein; variable resistances in said circuit, in series 40 with said selector switches, to balance the relative resistances to the generator, and thus to compensate for a line drop; a trip circuit of low resistance, having a series of terminals controlled by the action of the said 45 multiple circuit, but having no electrical connection with the multiple circuit; a registering circuit having a higher resistance than the trip circuit; a distant transmitting device to close and open the multiple circuit, and then to send a current through the trip 55 circuit at one resistance, and then through the registering circuit at a higher resistance.
52. A transmitting device; a selecting circuit; a selecting device; a trip circuit of low resistance; means controlled by the selecting device to close the trip circuit; a signal normally in the trip circuit; means controlled by the trip circuit to release and set the signal and thereby break the trip circuit; 60 means operated by the signal, to lock the signal in set position; a registering circuit having a higher resistance than the trip circuit; apparatus operated by the locking means to send impulses over the registering circuit characteristic of the signal set; and 65 means controlled by said impulses to register the fact that the signal has been set and locked; means to restore the signal and co-operating mechanism to normal position.
53. In a selective signal system, a two wire multiple circuit; interchangeable selector switches operatively connected therein; variable resistances in said circuit, in series 70 with said selector switches, to balance the relative resistances to the generator, and thus to compensate for a line drop; a signal; a trip circuit to release and set the signal and thereby break the trip circuit; means operated by the signal, to lock the signal in set position; a registering circuit having a 75 higher resistance than the trip circuit; apparatus operated by the locking means, to send impulses over the registering circuit characteristic of the signal set; and means controlled by said impulses to register the 80 fact that the signal has been set and locked; and means to restore the signal and co-operating parts to normal position.
- In testimony whereof I affix my signature in presence of two witnesses.
